THE NATIONAL LITHOGRAPHING COMPANY,
WASHINGTON, D. C.

UNITED STATES PATENT OFFICE.

GUSTAVE A. GELIEN, OF SAN FRANCISCO, CALIFORNIA.

ORE-GRINDER.

SPECIFICATION forming part of Letters Patent No. 508,008, dated November 7, 1893.

Application filed November 1, 1892. Serial No. 450,692. (No model.)

To all whom it may concern:

Be it known that I, GUSTAVE A. GELIEN, a citizen of the United States, residing in the city and county of San Francisco, State of California, have invented certain new and useful Improvements in Ore-Grinders, of which the following is a specification.

My invention consists in certain improvements in ore grinders which will first be fully described with reference to the accompanying drawings, and then pointed out in the claims.

In said drawings:—Figure 1 is a view in vertical section of my ore grinder. Fig. 2 is a plan or top view of the same. Fig. 3 is a view in detail of the device for raising and lowering the grinding shoes. Fig. 4 is a plan or top view of the ore-feeder or hopper.

A represents a tub or tank composed of wooden staves set on end as shown and suitably bound together by hoops and bolts and resting upon frame-work or timbers B, B. The staves composing the tub are made of considerable thickness at the base and incline downwardly and inwardly as at B^x, so as to impart strength to the tub and give lateral support to the outward pitch or inclination of the rim B² of the pan. By thus constructing the periphery or rim of the pan, the stone mullers can be more easily lifted and will not stick or adhere so closely to the rim as when made in a true perpendicular line.

On the bottom of the tub are placed the metal-plates or dies C, C, which constitute the grinding surface of the machine. They are laid in sections so that they can be removed from time to time when worn and are contained within the area of the two rim-plates D, D^x by which an annular grinding-trough is formed and sufficient annular space in the center of the machine is had for the operating mechanism. By this construction of pan the ore under treatment is confined in the narrow annular trough around the axis of revolution and consequently a more rapid reduction is had with less expenditure of power than where the ore is allowed to spread over a greater area or reducing surface. The inner rim-plate D is flanged as at D² and bolted to the floor or bottom of the tub and the outer rim plate D^x is made to fit closely against the side of the tub while the edge will rest upon the floor and afford a clean space between the

two rims for laying the plates or dies and forming the annular grinding floor or trough which is laid in sections meeting as at D³ D³. 55 These rim-plates may be cast whole or in sections properly supported and sustained when laid.

The grinders or mullers E E^x F F^x are composed of stone, and any rock of a sufficient 60 hardness and that will not wear away too rapidly will answer for the purpose. Four of these mullers or grinders are employed and thereby engage with the ore in the pan and reduce it to the desired degree of fineness for 65 amalgamation in the presence of quicksilver in the usual way. The grinders E E^x are of irregular shape and their outer edges are made rounding to engage with the circular rim of the pan as well as with the bottom floor 70 or dies, and are located diametrically opposite each other. The grinders represented at F F^x are quadrilateral in form and move around the inner rim of the pan also diametrically opposite each other. 75

Both series connect with the four arms G, G^x G^x of a turn table or plate H by means of the eye bolts 1, 1, and links or rods 2, 2, of the grinders E E^x and 3, 3, and 4, 4, of the grinders F F^x, the two latter grinders or 80 mullers being pivoted to turn table H by the straps I, I, by which they are held in a diagonal position to the axial line of the machine, and their inwardly beveled front ends f will tend to draw the pulp away from the periphery of the pan toward the inner rim and to the grinding faces of these inner mullers. 85

As a further means of directing the pulp away from the face of the inner rim of the pan and cause it to pass more completely under the grinders two diagonal wings or scrapers J, J, are connected to the arms G G of the turn-table the beveled points j of which follow in the rear of the grinders or mullers F, F^x and in close proximity with the inner rim 95 of the pan. They are raised or lowered by the levers I', I', pivoted at I^x I^x connecting with the scrapers by links I² I² and by rods I³ I³ which in turn connect with the collars I⁴ I⁴ upon the driving shaft of the machine. 100 From the collars extend the operating hand levers I⁵ I⁵ pivoted at I⁶ I⁶ having forked ends I⁷ I⁷ which engage with collars I⁴ I⁴ and by raising or lowering the levers the rods are

raised or depressed, the collars moving up or down on a feather of the shaft and the position of the scrapers is maintained by the hand levers engaging the teeth on the rack J^x .

5 Each of the four arms of the turn-table carrying the mullers or grinders is provided with a stay rod K, K, K, K , which rods connect with a collar K^x through which the driving shaft of the machine passes and to which it is keyed.

In order to raise up the forward ends of the mullers or grinders $E E^x$ a sufficient distance from the dies so that the pulp will pass under and come in contact with the grinding faces I have provided levers or gates $L L^x$ which are pivoted between their ends to ears l rising from supplemental arms g of the turn-table and extend outward in a diagonal manner and connect with the mullers by the eye bolts and links $L^2 L^2$. These levers are operated in the same manner as the levers which connect with the scrapers, that is to say by the rods $L^3 L^3$, collars $L^4 L^4$, levers $L^8 L^8$, and to the ends of the levers and rods is connected a cord or wire cable L^6 working in a sheave or grooved pulley L' and by operating the levers $L^8 L^8$ of the series the ends of the mullers or grinders are raised or lowered at will. By this construction and arrangement of grinders or mullers and wings or scrapers there will be little if any vortex of the pulp contained in the pan even though the pan be revolved at a rapid rate.

An ore feeding device consisting of a double funnel shaped hopper M is keyed to the driving shaft above the operating gate or lever. The bottom of this hopper is made inclining from diametrically opposite points $M^x M^x$ to diametrically opposite discharge openings $M^2 M^2$ so that the ore will gravitate toward the lowest depressions in the bottom—the discharging points, and from thence fall to the grinding pan; and for this purpose a hose pipe may be connected to the discharge openings for conducting the ore without splashing to the pan beneath. It will thus be seen that all the supporting and working parts of the machine are geared or keyed to the shaft the lower end of which passes through the bottom of the tub and is stepped on a cross timber of the supporting frame. The shaft is driven by the miter gears N, N , from a pulley N^x at the end of a horizontal shaft N^2 at a speed of about forty revolutions per minute. The ore is first crushed to about the size of peas and is fed along with water to the machine by a spout connecting with the hopper (not shown) and the reduction of the ore is known as wet reduction. As amalgamation takes place in a separate machine the reduced ore is taken from my grinding pan through a suitable discharge opening O .

Having thus described my invention, what I claim, and desire to secure by Letters Patent, is—

1. The combination in a grinding machine

of the character described, with an annular pan, an upright shaft in the center of said pan, radial arms carried by said shaft, and supplemental arms also carried thereby; of mullers within the pan, links connecting them with said arms, levers pivoted between their ends to ears on said supplemental arms and connected at their outer ends to said mullers, and means for depressing the inner ends of said levers at will, as and for the purpose set forth.

2. The combination in a grinding machine of the character described, with an annular pan, an upright shaft in the center of said pan, radial arms carried by said shaft, and supplemental arms also carried thereby; of mullers within the pan, links connecting them with said arms, levers pivoted between their ends to ears on said supplemental arms and connected at their outer ends to said mullers, pulleys mounted on said arms, sliding collars splined on said shaft, cords connected with said collars and passing under said pulleys to the inner ends of said levers, and forked hand-levers for adjusting said collars vertically, as and for the purpose set forth.

3. The combination with the stone mullers or ore grinders, of the pan constructed with an outwardly inclined or flaring rim, against which the outer faces of said mullers normally bear, and levers connected by upright links with the front ends of said mullers for raising only said ends at the times desired, as and for the purpose specified.

4. The combination of the wooden supporting tub with staves of increased thickness at the base, forming there inwardly inclined inner faces, and grooves below said inner faces for the tub-bottoms with the grinding pan having an outwardly inclined rim breasting against the inclined face of the tub, the bottom of the pan resting upon the tub-bottom, substantially in the manner as herein set forth and specified.

5. The combination with an ore machine of the character above described of the means for raising and lowering the irregular shaped mullers or grinders consisting of a vertical link connecting with one end of a lever and a flexible cord passing under a sheave or pulley connecting with the opposite end of the same lever, and a depressing rod connecting with a collar on the driving shaft in which a forked lever attached to uprights above the machine operates, as described.

6. The combination in a grinding machine of the character described, with an annular pan having raised inner rim, an upright shaft in the center of said pan, and a plate carried by said shaft and having radial arms; of quadrilateral grinders resting in the pan, straps connecting said plate and grinders and holding the latter in contact with the raised inner rim, the front ends of the grinders being loosely connected with said arms, scrapers carried by the arms in rear of the grinders

and having pointed front ends bearing against said rim, and means for raising said scrapers at will, as and for the purpose set forth.

7. The combination in a grinding machine of the character described, with an annular pan having raised inner rim, an upright shaft in the center of said pan, and a plate carried by said shaft and having radial arms; of quadrilateral grinders resting in the pan, straps connecting said plate and grinders and holding the latter in contact with the raised inner rim, the front ends of the grinders being loosely connected with said arms, scrapers carried by the arms in rear of the grinders

and having pointed front ends bearing against 15 said rim, levers centrally pivoted on the arms, links connecting their outer ends with the scrapers, collars splined on said shaft and connected with the inner ends of the levers, and forked hand-levers for raising and lowering said collars at will, as and for the purpose set forth.

In testimony that I claim the foregoing I have hereunto set my hand and seal.
